INFLATABLE TOY HORSE

Sol Passell, Youngstown, Ohio

Application March 14, 1955, Serial No. 35,010

Term of patent 3½ years

(Cl. D34—15)

Figure 1 is a perspective view of an inflatable toy horse, showing my new design, the opposite side having substantially the same appearance; and

The broken line showing of a child carrying the toy horse is for illustrative purposes only.

I claim:

The ornamental design for an inflatable toy horse, as shown and described.
